Caleb W. Palmer, of Troy, N.Y.
Letter's Patent No. 1504, dated April 15, 1862.

The shield referred to in these Letters Patent and making part of the same.

To all whom it may concern:

Be it known that I, Caleb W. Palmer, of the City of Troy, in the County of Rensselaer, and State of New York, have invented or produced a new and original ornamental design for a Cooking Stove; and I do hereby declare that the following is a full and exact description of the same, reference being had to the annexed photographic drawing of a stove having

Des. 1564

my said ornamental design.

The distinguishing feature of my said ornamental design for a cooking stove is the particular plaid, checked ground work, a, and the rosette, b, or lettered tablet, c, all respectively shaped and arranged on the front and end doors or panels of the fire box portion, D, and on the end doors, and front panel of the elevated oven E, of the stove, as shown by the annexed photograph.

What I claim as new and of my invention or production and desire to secure by Letters Patent, is an elevated oven cooking stove ornamented as above described.
